UNITED STATES PATENT OFFICE.

THOMAS H. GULICK, OF ST. LOUIS, MISSOURI.

BRUSH.

SPECIFICATION forming part of Letters Patent No. 606,713, dated July 5, 1898.

Application filed August 16, 1897. Serial No. 648,416. (No model.)

To all whom it may concern:

Be it known that I, THOMAS H. GULICK, a citizen of the United States, residing at St. Louis, State of Missouri, have invented certain new and useful Improvements in Scrubbing-Brush Holders, of which the following is a full, clear, and exact description, reference being had to the accompanying drawings, forming a part thereof.

10 My invention has relation to improvements in holders for scrubbing-brushes; and it consists in the novel arrangement and combination of parts more fully set forth in the specification, and pointed out in the claims.

15 In the drawings, Figure 1 is a transverse section of the device, taken on the line $x-x$ of Fig. 2; and Fig. 2 is a longitudinal section on line $y-y$ of Fig. 1.

The object of my invention is to construct 20 a holder for scrubbing-brushes which while it subserves the purpose of temporarily holding the brush at the same time serves as a means of feeding water thereto, and also serves as a receptacle for a bar or cake of soap or 25 similar detergent, which is gradually dissolved by the water fed to the brush.

In detail the invention may be described as follows:

Referring to the drawings, 1 represents the 30 casing or chamber of the holder, the upper wall thereof being provided with a socket 2 for the reception of the lower end of a suitable handle, (not shown,) there being hinged along the base of the socket a lid 3, the edges 35 of which are provided with a depending flange 4, adapted to close against the inner surfaces of the walls of the casing, a strip of packing 5 being interposed between the projecting edges of the door and the upper edges 40 of the walls of the casing to make a watertight joint. To retain the door in a tightly-closed position, I pivot to a lug 6, carried by the outer surface of the wall adjacent to the free end of the lid, a screw-threaded bolt 7, 45 which is adapted to pass through a fork 8 of the lid, a tightening-nut 9 being subsequently forced down against the lid. The inner surface of the lid is provided with a tapering knob 10 of sufficient length to enter and 50 firmly press against a cake of soap 11, supported along the parallel-disposed ribs 12 at the bottom of the casing, the soap being fur-

ther retained in place by the knobs 13 14, carried, respectively, by the inner surface of the outer wall of the casing and the base 55 of an angular deflecting plate or wall 15, located at the opposite end of the casing, the deflecting-wall forming, with the bottom wall of the socket or top wall of the casing, a passage 15', which communicates with the nozzle 60 16, the nozzle being provided with a controlling valve or cock 17 to shut off the water when desirable. To the free screw-threaded end of the nozzle is secured the hose 18.

As seen in Fig. 1, the socket 2 is located above 65 the nozzle, so that the hose will not be in the way of the operator while manipulating the handle carried by the socket.

From the base of the casing 1 depend the 70 terminal passages 19, deflected inwardly at 20, the inner adjacent walls of said passages 19 and the upper walls of the deflected portions 20 forming parallel grooves 20' for the reception and retention of the back of the brush 22, the latter being prevented from 75 slipping out of its bearings by the locking-arm 23, hinged along one of the lateral walls of the casing and swung into locking position after the brush has been once inserted, the opposite end of the brush being held by 80 coming in contact with the lower end of the wall 24. The free adjacent ends of the deflected passages 20 are provided with slits 21, (or a series of openings which would be a full equivalent,) the same being inclined to the 85 horizontal and converging toward one another, so as to permit the discharge of the water against the bristles of the brush in converging streams, thus supplying the brush with water charged more or less with the 90 saponaceous solution from the soap, over the surface of which the water flows.

During the scrubbing of woodwork, doorsteps, sidewalks, stone surfaces generally, &c., just enough water can be turned on 95 through the valve 17 as is necessary to act on the soap and dissolve the same to the desired degree. When the scrubbing operation is concluded, the soap can be withdrawn and a full stream of water turned on, thus 100 flushing the surface previously scrubbed. By the use of the present invention much water can be saved which is now generally allowed to go to waste.

It is apparent, of course, that minor changes might be made in the device without departing from the spirit of my invention.

Having described my invention, what I claim is—

- 5 1. In a scrubbing-brush holder, a suitable casing adapted to hold a cake of soap, a nozzle communicating with the chamber of the casing, a socket for securing a handle to the casing located at a point above the nozzle, a lid for the casing located adjacent to the base of the socket, means for holding a cake of soap within the casing and permit the free flow of water about the surface of the soap, 10 suitable discharge-openings leading from the casing, and a brush adapted to be carried by the casing in proximity to the discharge-openings whereby the water is fed to the brush, substantially as set forth.
- 15 2. In a scrubbing-brush holder, a suitable casing, a nozzle communicating with the chamber thereof, a deflecting-wall interposed between the nozzle and chamber of the cas-

ing, a lid hinged to the upper wall of the casing, a knob carried by the inner surface of the hinge, suitable supporting-ribs disposed along the bottom of the casing and adapted to support a cake of soap, soap-retaining knobs carried by the deflecting-wall and the wall of the casing opposite thereto, outlet-passages leading from the casing at opposite ends thereof and forming by their walls suitable grooves for the reception of the back of a brush, a locking-arm for retaining the brush within its supporting-grooves, and suitable discharge openings or slits leading from the outlet-passages and arranged to discharge in converging streams against the brush, substantially as set forth.

In testimony whereof I affix my signature in presence of two witnesses.

THOMAS H. GULICK.
